S. H. RANSOM, OF ALBANY, NEW YORK.

Letters Patent No. 91,563, dated June 22, 1869.

COOKING-STOVE.

The Schedule referred to in these Letters Patent and making part of the same

To all whom it may concern:

Be it known that I, S. H. RANSOM, of the city and county of Albany, and State of New York, have invented certain new and useful Improvements on Cooking Stoves; and I do hereby declare that the following is a full, clear, and exact description thereof, reference being had to the accompanying drawings, making part of this specification, in which—

Figure 1, sheet 1, is a section taken longitudinally through the centre of my improved stove, in the vertical plane indicated by line z , in fig. 2.

Figure 2, sheet 1, is a top view of the stove.

Figure 3, sheet 2, is a section taken transversely through the upper portion of the stove, in the vertical plane indicated by line $z z$, in fig. 1, looking rearward.

Figure 4, sheet 2, is a transverse section taken through the stove in the vertical plane indicated by line $y y$, in fig 1, looking rearward.

Figure 5, sheet 2, is a perspective view of a removable rear flue-extension or pipe-connection of the stove.

Similar letters of reference indicate corresponding parts in the several figures.

This invention relates to improvements on that class of cooking-stoves which have chambers extended in rear of their back plates, and which are denominated extension-top stoves.

The nature of my invention consists—

First, in so arranging the flues and damper of an extension-top stove, that all of that portion of the chamber formed by the extension of the upper portion of the stove shall be free to receive the heated products of combustion before they enter the flues below the top plate of the oven, whether the damper be closed against the direct draught or not, as will be herein-after explained.

Secondly, in a removable cast-metal elbow or flue-extension, which is applicable to an extension-top stove, for receiving the stove-pipe, and which can be readily removed when the stove is packed for transportation, as will be hereinafter explained.

To enable others skilled in the art to understand my invention, I will describe its construction and operation.

In the accompanying drawings—

A represents the fire-chamber of the stove;

B, the oven; and

$a a$, horizontal sheet-flue, which extends from the fire-chamber A, over the oven, over the flues $a' a' b$, to the rear end of the rear extension E, thus forming an unobstructed flue-space beneath the entire bottom surface of the top plate D, of the stove.

The top plate D is constructed with two pot-holes, arranged over the fire-chamber A, two holes over the top oven-plate c, and two arranged over the vertical flues $a' a' b$, and extension E, as shown in fig. 2.

Between the rear extension E, and the rear wall of the oven B, are three vertical flues, which are formed by this wall on one side, the rear wall j of the body of the stove on the other side, and two vertical division-plates C-C, which latter extend beneath the oven nearly to the front wall of the stove.

The upper ends of these plates C-C terminate on a level, or nearly so, with the top-plate of the oven, at a point between the horizontal sheet-flue a , and the escape-flue b , and they form a central flue for the return-draught, and also two side flues $a' a'$, for conducting the products down behind the oven, and beneath its bottom plate, to the front opening of the return-flue b .

At or near the upper terminus of the vertical portion of the return-flue b , and at a point which is above the escape-orifice of flue b , a damper, h , is arranged, as shown in figs. 1, 2, and 4.

By shutting this damper, as shown in fig. 1, the products of combustion, after circulating in the entire space a , will descend through flues $a' a'$, pass forward beneath the oven, and thence enter return-flue b , and escape into b' , beneath the damper.

When this damper h is open, the products will also circulate in the entire space a , as before, but descend directly into b , and pass off through b' .

Thus it will be seen that the chamber in the extension E is exposed to the action of the highly-heated products passing from the fire-chamber before the products descend into the flues $a' a' b$, whether the direct draught be closed or open.

The escape-orifice is made through the back-plate j , immediately beneath the rear extended portion E, and from this orifice the products are carried through an elbow extension F, on their way to the smoke-pipe.

This elbow is removable, and when it is applied to the stove it fits snugly beneath the extension E, and is held securely in place by a hooked lug, f , and one or more screws g , as shown in fig. 1. Instead of applying the screw-fastening g , through the bottom of the extension E, as shown in fig. 1, it may be passed through that portion of the rear edge of top plate D which extends over the upper surface of the elbow F.

This elbow is constructed with a pipe-collar, f' , upon its upper end, which end is nearly in the horizontal plane of the stove-top D, and when it is desired to pack the stove for transportation, the elbow is removed.

The top plate c of the oven B, is corrugated, so as to form valleys or depressions, running longitudinally between the two rows of pot-holes through plate D, and to leave in the centre of this plate an elevation or ridge, as shown in fig. 3.

By thus constructing plate c, I not only protect it from cracking by expansion and contraction, but I

also enlarge the depths of the passages for the products of combustion directly beneath the pot-holes, so that the greatest amount of heat will be concentrated at these points.

Having thus described one practical mode of applying my invention to a three-flue cooking-stove, I do not mean to be understood as limiting myself to the precise arrangement shown, as the invention is also applicable to stoves having broad sheet-flues, two flues, or in fact any of the known flues. It is also equally applicable to stoves with oven enlarged or extended, or that the rear back-plate of the flue *j* may be about in vertical line with back of top plate.

What I claim as new, and desire to secure by Letters Patent, is—

1. Such an arrangement, in an extension-top cooking-stove, as will allow all that portion of the chamber formed by the rear extension of the upper part of the stove, to receive the heated products before they enter the flues below the top plate of the oven, whether the

direct-draught damper be closed or open, substantially as described.

2. In combination with the free space *a*, extending horizontally from the fire-chamber into the chamber formed by a rear extension, *E*, a damper, *h*, or its equivalent, arranged below said space *a*, but above the escape-passage *b'*, substantially as described.

3. Flue-plates *C C*, terminating at their upper ends on a level, or nearly so, with the top plate of oven *B*, in combination with flues *a' a'* and *b*, and a damper, arranged substantially as described.

4. The portable elbow-extension *F*, arranged below the extension-chamber *E*, and secured by a hook, *f*, and a screw-fastening, *g*, substantially as described.

5. The relative arrangement of *a*, *E*, *F*, *h*, and *C*, substantially as described.

S. H. RANSOM.
